UNITED STATES PATENT OFFICE.

GEORGE H. JENKINS, OF OAK PARK, ILLINOIS.

BINDER.

1,180,927.

Specification of Letters Patent. Patented Apr. 25, 1916.

Application filed July 25, 1914. Serial No. 853,109.

To all whom it may concern:

Be it known that I, GEORGE H. JENKINS, a citizen of the United States, residing at Oak Park, in the county of Cook and State 5 of Illinois, have invented certain new and useful Improvements in Binders, of which the following is a specification.

This invention relates to a binder within which a quantity of loose leaves may be held, and has particular reference to the 10 construction of the covers by which a transfer of contents to permanent covers may be expeditiously effected.

Among the principal objects of my invention 15 is the provision of means for enabling the transfer of the contents to be made from temporary covers to permanent covers with a minimum of labor, expense and delay; and, as will more fully hereinafter appear, 20 the invention consists also in numerous other features of construction and combinations of parts.

In the drawing: Figure 1 is a perspective view of a quantity of leaves bound together 25 between permanent covers; Fig. 2 is a transverse section through the leaves and covers showing the relation of the parts at one stage of the binding operation; and Fig. 3 is a detail showing connecting means capable 30 of use for effecting a permanent binding.

In ordinary practice, a quantity of leaves 4 is bound between temporary covers 5 through suitable means such as the posts 6 35 shown in Fig. 2, a screw cap 7 being arranged to thread upon the upper end of each post 6 to bear against the leaves with the desired pressure. At the time the leaves are arranged within the binder, it is 40 contemplated that one of the permanent covers 8 will be installed in position as shown in Fig. 2, the other permanent cover 9 being placed in operative position only at the time the permanent binding is to be effected.

The posts 6 are secured to one of the temporary covers 5 in any approved manner, and extend through registering openings 10 in each of the leaves 4, and permanent covers 8 and 9, as well as the upper temporary 50 cover 5 which is engaged by the screw 7. As shown in the drawing, two posts 6 are provided, it being obvious that this number may be varied according as conditions may require. In addition to the openings 10 through which the posts 6 project, I have provided other registering openings 11

through which posts 12 may extend as shown in Fig. 2. In line with such openings enlarged registering openings 13 are arranged in the temporary covers enabling the 60 head 14 of the post 12 to pass therethrough to abut against the permanent cover 8, and enabling a cap 15 to pass similarly into position against the other permanent cover 9. As shown in Fig. 3, the cap 15 maintains a 65 screw-threaded connection with the post 12 through a shank 16 which engages within a socket 17. A slot 18 within the cap facilitates rotation of the cap when a screw driver or other similar instrument is employed to 70 bring about the desired amount of compression.

Whenever it is desired to transfer leaves from the temporary to the permanent covers, the upper or second permanent cover 75 9 is arranged in the position shown in Fig. 2, the temporary cover 5 which was theretofore removed for such purpose being replaced temporarily in position again. The desired compression of the leaves is brought about by manipulation of the screw caps 7, after which the posts 12 are inserted into position, the cap 15 being screwed in place as shown in Fig. 2. It is obvious that the posts 12, together with the head and caps attached thereto, each maintain the leaves in bound 80 relation independent of the binding action of the posts 6. For this reason the covers 5 may be removed from the bound volume, the posts 6 for such purpose being withdrawn from the openings 10. Under such 85 conditions, the bound volume remains intact, the permanent binding being maintained between the covers 8 and 9 by the posts 12. The covers 5, it is manifest, are 90 available for further use with fresh leaves.

When it is considered that the temporary covers used for current work are subjected to hard usage and on this account must be 95 carefully constructed, the advantage in saving such covers for continuous work is readily apparent. The permanent covers in which the leaves are ultimately bound need not however be of the same construction, since such volumes are used principally for 100 reference work as distinguished from current use. A considerable saving in cost is obtainable by the use of two sets of covers in the manner described.

From the foregoing it will be apparent 110 that my invention contemplates a construction of binder covers which will permit of a

transfer of contents with scarcely any labor, time or extra expense involved. The particular form of binding means used is of secondary importance, and although posts 5 have been mentioned for this purpose other equivalent means would obviously answer.

I claim:

1. In combination with a quantity of stacked leaves, a cover arranged adjacent 10 said stack of leaves, removable means for binding said cover and leaves together, and other means for binding together said leaves independent of the cover, there being openings through said cover through which said latter binding means may be placed in operative position, substantially as described.

2. In combination with a quantity of stacked leaves, a binder embodying covers arranged adjacent said stack of leaves, 15 means for binding said covers and leaves together capable of removal from operative position, and other means for binding together said leaves independent of the cov-

ers, there being openings through said covers through which said latter binding means 25 may be placed in operative position, substantially as described.

3. In combination with a quantity of stacked leaves, a binder embodying covers arranged adjacent said stack of leaves, removable means for binding said covers and leaves together, and other means for binding together said leaves independent of the covers consisting of a binding element arranged to pass through the stack of leaves 30 having an enlarged portion at each end thereof to engage with the outermost leaf, there being openings through said covers through which each of said head portions may pass to engage only with said outermost leaf.

GEORGE H. JENKINS.
